UNITED STATES PATENT OFFICE.

JOSEPH L. FIRM, OF BERWYN, ILLINOIS, ASSIGNOR TO THE GOSS PRINTING PRESS COMPANY, OF CHICAGO, ILLINOIS, A CORPORATION OF ILLINOIS.

PRINTING-PRESS.

1,100,066.

Specification of Letters Patent. Patented June 16, 1914.

Application filed June 30, 1913. Serial No. 776,595.

To all whom it may concern:

Be it known that I, JOSEPH L. FIRM, a citizen of the United States, residing at Berwyn, in the county of Cook and State of Illinois, have invented certain new and useful Improvements in Printing-Presses, of which the following is a specification, reference being had to the accompanying drawings.

10 This invention relates to printing presses of the web perfecting type, and has for one of its objects to provide a new and improved form of tubular printing plate over that shown and described in patent issued to me on May 8, 1900, No. 648,938.

It has for another object the provision of a new and improved form and arrangement of press whereby the webs can be associated and folded into a great variety of different 20 products.

It is another object of my invention to provide a more compact and cheaper printing mechanism than has been ordinarily in use heretofore, adapted to use also printing plates which may be produced more rapidly 25 and at less expense.

It is another object of my invention to provide a new and improved inking mechanism by which all the printing plates at 30 one side of the machine may be inked by a single device.

It is another object of my invention to improve printing presses of this type in sundry details hereinafter pointed out.

35 The means by which I have accomplished these objects are illustrated in the drawings and are hereinafter specifically described. That which I believe to be new is set forth in the claims.

40 In the drawings,—Figure 1 is a diagrammatic side view of my improved press; Fig. 2 is a top or plan view of the associating and folding mechanism located between two sections of press; Fig. 3 is an end view of 45 the press; Fig. 4 is an end view of one of the tubular plates; Fig. 5 is a view of the plate in Fig. 4 as seen from the right therein; and Fig. 6 is a perspective view of a modified form of plate.

50 In the drawings,—10 indicates the frame of one section of my press, and 11 indicates the frame of another section thereof. As best shown in Fig. 1, 12 indicates a roll of paper mounted in any suitable way adjacent to the impression cylinder 13 carried

55 cent to the impression cylinder 13 carried

by the frame 10 at one end. 14 indicates a plate cylinder, the shaft 15 of which is mounted at one end in the frame 10 and at the other end in an arm 16 projecting horizontally on the frame 10, said arm 16 being of such a thickness vertically that the slotted tubular plate 17 is adapted to be mounted upon the cylinder 14 by being slipped upon one end of said cylinder with the slot of the plate passing over the arm 16. 18 indicates a second tubular plate adapted to be slipped upon the cylinder 14 in like manner with plate clamps 19 of any approved type interposed between said two plates, the plates 17—18 being locked upon the cylinder 14 in any well-known approved manner. 20 indicates the web of paper passing between the impression cylinder 13 and the plate cylinder 14 from the roll 12, and from thence about the impression cylinder 21 journalled above the impression cylinder 13. 22 indicates a plate cylinder journalled above the plate cylinder 14 and adapted to coact with the impression cylinder 21. 23 indicates the arm extending horizontally from the frame 10 upon which the end of the plate cylinder 22 is mounted. 24 indicates a roller down about which the web 20 passes from the impression cylinder 21, and 25 indicates an angle-bar about which the web 20 passes for being deflected laterally from the press, as shown in Fig. 3. The mechanism at the other end of this section of the press is similar to that just described, but oppositely arranged. At this end of the machine, 26 indicates the roll of paper, the web 27 from which passes first between the impression cylinder 28 and the plate cylinder 29 provided with a tubular plate 30.

31 indicates the horizontal frame arm by which the end of the plate cylinder 29 is supported.

32 indicates the impression cylinder located above the impression cylinder 28, and 33 indicates the upper plate cylinder supported by the horizontal frame arm 34.

35 indicates the tubular plate mounted upon the cylinder 33.

36 indicates the roller around which the web 27 passes from the cylinders 32—33, and 37 indicates the angle-bar by which the web 27 is deflected laterally from the press.

38—39 indicate slitting devices adjacent to the rollers 24—36, respectively, and movable into and out of contact with the webs pass-

110

ing over said rollers whereby when desired said webs can be slit along their central longitudinal lines. It will be understood that the slitters 38-39 will be used principally when the plate cylinders are made of a size to accommodate four plates abreast rather than when the cylinders are made as shown to accommodate only two plates abreast. When the cylinders are made four plates wide the webs are to be slit longitudinally by the slitters 38-39, and associated by any suitable means for passing over a two plate wide former, as for example by the means shown in United States Patent No. 676,816, granted to me on June 18, 1901.

40 indicates an inking fountain provided with feed rollers 41-42.

43-44-45-46 indicate fountain rollers adapted to be reciprocated by any suitable mechanism not shown for inking the drums 47-48-49-50, respectively.

51 indicates distributing rollers by which the ink is spread upon the drums 47-48-49-50, and 52 indicates form rollers by which the ink is delivered from the ink drums to the printing press upon the plate cylinders, as is well understood in the art.

As will be readily understood, the mechanism carried by the frame 11 is similar to that just described and it is accordingly believed that it is not necessary to describe such mechanism in detail.

In Fig. 3, 53 indicates the roll of paper. 35 54 indicates the impression cylinder shown, and 55 indicates the web leading from the roll 53 and extending laterally from the machine. As best shown in Fig. 3, the webs 20-55 at one end of the machine are associated together between rollers 56-57, and as shown in Fig. 2, the web 27 above referred to and the web 58 from the corresponding end of the section of press supported by the frame 11 are associated between similar rollers 59. 60 indicates a former over which the webs 55-20 are led, the central longitudinal fold being completed by rollers 61-62, as will be readily understood. The webs 58-27 are likewise led over a former 63, the central longitudinal fold being laid by rollers 64-65. 66-67 indicate rollers between which the centrally folded webs pass on their way to the cutting cylinder 68 and the folding cylinder 69 which are of any approved type for the delivery of the complete folded product. If desired, the form of folder shown in my United States Patent No. 868,855, may be used, delivering two complete products.

60 In Fig. 6 I have shown a modified form of plate comprising two plates 70-71 formed integrally with each other. By the use of this form of plate considerable time in the casting and finishing of the plate is 65 saved, as well as some little time in mount-

ing the plate upon the press. So far as I am aware, I am the first in the art to provide for the use of a double tubular plate of the type shown in Fig. 6, and my claims are to be construed accordingly. So far as I am aware, I am the first in the art to provide an inking mechanism by which the printing mechanisms at both ends of a press may be inked from a single fountain, and I therefore claim this feature broadly.

That which I claim as my invention, and desire to secure by Letters Patent, is,—

1. In a printing press, the combination of a printing mechanism at one end of the press comprising two printing couples, a printing mechanism at the other end of said press comprising two printing couples, an inking fountain, and means for applying ink from said fountain to each of said printing couples.

2. In a printing press, the combination of a printing mechanism at one end of the press comprising two printing couples one located above the other, a second printing mechanism at the other end of the press comprising also two printing couples one located above the other, an inking fountain, means for applying ink from said fountain to each of said printing couples, and means for turning the printed webs laterally relative to their run through the printing mechanisms.

3. In a printing press, the combination of a printing mechanism at one end of the press comprising two printing couples one located above the other with each of the impression cylinders arranged outside relative to the plate cylinder, an inking fountain, and means for applying ink from said fountain to each of said plate cylinders.

4. In a printing press, the combination of a printing mechanism at one end of the press comprising two printing couples one located above the other, a second printing mechanism at the other end of the press comprising also two printing couples one located above the other, each of the impression cylinders of said printing couples being arranged outside relative to the plate cylinder, an inking fountain, and means for applying the ink from said fountain to each of said plate cylinders.

5. In a printing press, the combination of a frame, impression cylinders journaled therein one at each end thereof, arms extending horizontally inward from said impression cylinders, plate-cylinders journaled in said horizontally-extending arms whereby slotted tubular plates are adapted to be inserted on said plate-cylinders over said arms, and an inking mechanism located between said two plate-cylinders adapted to ink the plates on both of said cylinders.

6. In a printing press, the combination of a frame, impression cylinders journaled

therein one above the other, arms extending horizontally inward from said impression cylinders, plate-cylinders journaled in said horizontally-extending arms whereby slotted 5 tubular plates are adapted to be inserted on said plate-cylinders over said arms, and an inking mechanism at approximately the middle point of said press for applying ink to the plates on both of said plate-cylinders.
